UNITED STATES PATENT OFFICE

WILFRID THOMAS MINETT, OF LEICESTER, ENGLAND, ASSIGNOR TO UNITED SHOE MACHINERY CORPORATION, OF PATERSON, NEW JERSEY, A CORPORATION OF NEW JERSEY

SEWING MACHINE

Application filed September 19, 1930, Serial No. 483,026, and in Great Britain October 8, 1929.

This invention is concerned with improvements in or relating to sewing machines and is particularly concerned with the locking thread mechanism of lockstitch sewing machines.

Lockstitch sewing machines are used in the boot and shoe industry for sewing on the outsoles of shoes and a machine of the kind frequently used for this purpose is a machine as shown in the patent to Ashworth No. 1,169,909 dated February 1, 1916. The machine shown in this patent makes use of a rotary loop taker in the form of a rotary hook having a loop taking beak and housing within it a spool of thread on a bobbin in a case therefor, the bobbin being held against rotation with the loop taker and a loop of under-thread being taken up by the beak during the sewing of a seam and carried around the bobbin case and over the thread issuing from the bobbin to form a lockstitch. In such a machine it has been usual to provide pins which engage the bobbin case to hold the latter (and therefore the bobbin within it) against rotation with the loop taker and a cam ring has usually been provided which extends round the interior of the bobbin case housing in the loop taker and which acts to engage said pins during the rotation of the loop taker and moves them alternately away from engagement with the bobbin case to allow the loop of under-thread to pass round the bobbin case without being obstructed by the pins. The presence of the cam ring within the bobbin case housing notably decreases the internal diameter of the housing and therefore reduces the size of the bobbin case and bobbin which can be inserted therein and imposes a corresponding limitation upon the thread-holding capacity of the bobbin.

It has not hitherto been considered possible to arrange for the use of a larger bobbin in a machine of the kind above indicated without increasing the size of the loop taker and changing the position or size of other instrumentalities of the machine which have to co-operate with the loop taker in the sewing of the lockstitch seam.

One of the several objects of the present invention is to provide a loop-taker suitable

for use in a machine of the kind hereinbefore indicated which will be so arranged as to be capable of housing within it a bobbin of larger thread-holding capacity than usual hitherto but which will have external dimensions similar to those of loop takers at present in general use in such machines.

Another of the several objects of the present invention is so to arrange a loop taker suitable for use in a lockstitch shoe sewing machine that it will be simplified and of more robust construction than heretofore usual.

In order that the present invention may be more clearly understood there will now be described, by way of example only and with reference to the accompanying drawing one construction, assumed to be for use in a machine as described in said patent, which is illustrative of the various features of the invention.

In the drawing:

Figure 1 is a side elevation, partly in section, showing a loop taker embodying features of the present invention and containing a bobbin of thread; and

Figure 2 is a plan view of the loop taker seen in Figure 1.

The illustrative loop taker comprises a tubular body 1 providing within it a housing 3 for a spool of thread on a bobbin 5. A ring-like member 7 is secured, by screws, to one end of the body 1 as shown and extends around the greater part of its periphery and has at one end thereof a loop taking beak 11. Close to the opposite end of the loop taker body the latter is provided around its periphery with bevelled gear teeth 13 with which the driving pinion is adapted to mesh. A shoulder 15 provided around the inside of the ring-like member 7 is adapted to form with the adjacent end face of the loop taker a rectangular groove as shown. The bobbin case 17 has a peripheral rib 19 therein which is adapted to be received within the said groove to position the bobbin case within the loop taker. The bobbin case has a split sleeve 21 extending axially thereof and upon this sleeve the bobbin 5 is adapted to fit with a good friction fit the bobbin being of such diameter as to fit snugly within the bobbin case. A hollow fixed member 25 adapted

to be secured to the front of the machine frame by screws 27 as indicated in Figure 2 is of such a size as to receive freely within it the forward end of the loop taker which 5 has the gear teeth 13 aforesaid therearound, the loop taker being held in this position by appropriate means. The member 25 has extending axially from it a sleeve 29, the external diameter of which is only very slightly 10 less than the internal diameter of the loop taker so that the sleeve may extend within the latter more or less tightly and support it during its rotation. The said sleeve 29 is of such a length that when fitting within 15 the loop taker it extends fairly closely up to the near end of the bobbin case 17 but nevertheless leaves room between it and the bobbin case for a loop of under-thread to pass easily around the bobbin case. Two 20 grooves are provided in the periphery of the sleeve 29 extending parallel to its axis at more or less diametrically opposite points thereon. Sliding fingers 31 are housed within the said grooves and these fingers are of 25 such a length that they may extend beyond the inner face of the sleeve 29 for a substantial distance while their opposite ends are approximately flush with the outer face of the member 25. The thickness of that part 30 of said fingers which extends into the interior of the loop taker is more or less equal to the depth of the grooves so that the outer faces of the fingers are more or less level with the outer periphery of the sleeve 29. 35 Rat trap springs 33 are provided on the front of the member 25 to bear against the outer ends of the fingers 31 to urge them along their grooves toward the bobbin case 17. The bobbin case has slots 35 cut in that edge 40 thereof which lies nearer to the fingers within which slots the inner ends of the said fingers 31 may be received one or other of the fingers being at all normal times in its slot. This arrangement ensures that the bobbin case shall be held stationary during the 45 rotation of the loop taker. To provide that the said fingers shall be withdrawn along their grooves away from the bobbin case at appropriate times to allow a loop 37 (see 50 Figure 1) of underthread picked up by the loop taker beak 11 to pass around the bobbin case in a well-known manner the cylindrical body 1 has on that end which surrounds the sleeve 29 a cam face 39 which projects axially 55 of the end of the cylindrical body a distance of about three sixteenths of an inch and extends around the loop taker for about one third of its periphery the ends of the cam face being bevelled as shown in Fig. 2. Each 60 finger 31 is provided along its length with a shoulder 41 with which the cam 39 is adapted to engage during rotation of the loop taker to withdraw each finger in turn from its slot in the bobbin case in order to allow the 65 under-thread 37 to pass between the finger

and the case as indicated in Figure 1. Since as aforesaid the said fingers 31 are spaced approximately diametrically across the sleeve 29 and the cam 39 extends around the periphery of the loop taker for about a third only 70 of its length it will be understood that only one of the fingers 31 will be urged by the cam rearwardly at any time so that the bobbin case will at all times be held against rotation 75 in spite of the withdrawal of one or other of the fingers. The bobbin itself will therefore be held against rotating with the loop taker but can nevertheless be rotated on its supporting sleeve 21 by the drawing off of the bobbin thread during the sewing operation. By arranging the cam at the end of the loop taker as described instead of on the inside of the housing for the bobbin case it is possible to house a bobbin of considerably 80 larger diameter in the loop taker. In loop 85 takers of the kind hereinbefore indicated which have a cam ring inside the bobbin case housing for withdrawing the retaining pins away from engagement with the bobbin case at certain times, the cam ring has usually 90 been positioned on the body 1 close to the root of the beak 11 and it has been necessary to provide for a substantial gap between the rear edge of the cam and the forward end 95 of the bobbin case axially of the loop taker in order to allow the loop of under-thread to pass easily around the bobbin case between the latter and the cam ring. This fact imposes a serious limitation on the width of 100 the bobbin case (and therefore of the bobbin) which can be used. In the illustrative construction according to the present invention however there is no cam ring in the interior of the loop taker and the width of 105 the loop taker may therefore be considerably increased, the extent of the increase being limited chiefly by reason of the fact that the loop of under-thread must slide easily from the loop taking beak (which is fixed in position on the shuttle) over the bobbin case 110 and this becomes more difficult if the width of the bobbin is very largely increased. A loop taker of the internal cam-ring type above mentioned and adapted to fit into the machine described in the said patent has 115 usually carried a bobbin the dimensions of which were approximately—, diameter, one and seventeen thirty seconds of an inch and width between the flanges, nine sixteenths of an inch. A loop taker of the same size constructed as above indicated in accordance with the present invention can accommodate a bobbin of which the dimensions are diameter one and nineteen thirty seconds of an inch and width between flanges three quarters of an inch, showing an increased thread capacity of about fifty per cent. 120

The invention having been thus described what is claimed is:—

1. The combination with a loop taker, suit- 130

able for use in a shoe sewing machine, adapted to move in a circular path and having within it a housing for a spool of thread, of retaining means arranged to retain the spool 5 against rotary movement with the loop taker and withdrawing means, exterior to the housing for the spool, for engaging said retaining means at a certain time during the sewing of a stitch to withdraw said retaining 10 means from retaining position to allow thread to pass between the retaining means and the spool.

2. The combination with a loop taker, suitable for use in a shoe sewing machine, adapted 15 to move in a circular path and having within it a housing for a mass of thread and a case for the thread mass, of retaining means comprising retractable fingers extending into the said housing to engage the case and retain 20 the same stationary during the movements of the loop taker and withdrawing means arranged on the loop taker body exterior to the housing for urging the said fingers away from the case at certain times 25 during the movements of the loop taker.

3. The combination with a loop taker suitable for use in a shoe sewing machine adapted to move in a circular path and having within it a housing for a mass of thread and 30 a case for the thread mass, of retaining means comprising retractable fingers extending into the housing to engage the case and retain the same stationary during the movements of the loop taker, and withdrawing means 35 for said retaining means comprising a cam member located on the outer face of the loop taker and arranged to engage said fingers during the movements of the loop taker.

4. The combination with a loop taker suitable 40 for use in a shoe sewing machine adapted to move in a circular path and comprising a tubular body having a loop taking beak at one end thereof and providing a housing for a thread case, retractable fingers arranged 45 to engage the thread case and retain the same stationary during the movements of the loop taker, and withdrawing means for said fingers comprising an arcuate cam on the end 50 of the tubular body opposite the loop taking beak extending axially of the body and arranged to engage said fingers.

5. The combination with a loop taker suitable 55 for use in a shoe sewing machine adapted to move in a circular path and comprising a tubular body having a loop taking beak at one end thereof and providing a housing for a thread case, retractable fingers arranged to engage the thread case and retain the same 60 stationary during the movements of the loop taker, yielding means exterior to the housing for urging said fingers into position to engage the thread case, and withdrawing means for said fingers comprising an arcuate 65 cam on the end of the tubular body opposite

the loop taking beak extending axially of the body and arranged to engage said fingers.

In testimony whereof I have signed my name to this specification.

WILFRID THOMAS MINETT.
